BALL-ACTUATED RACING GAME DEVICE

William A. Malkan, New York, N. Y.

Application July 10, 1948, Serial No. 38,107

4 Claims. (Cl. 273—86)

1

This invention relates to a game device which simulates a horse race or the like.

An object of the invention is to provide a game device in which racing elements are propelled down inclined guide tracks by striking engagement of rollable members therewith.

Another object of the invention is to provide a racing game device of said character in which rollable members are moved into position for striking engagement with the racing elements independently of the control or skill of the players.

Another object of the invention is to provide a racing game device in which certain of the rollable members are interrupted in their movement into position for striking engagement with the racing elements so as to render uncertain the number of rollable members striking each racing element during the game.

Another object of the invention is to provide a racing game device in which the players do not handle or manipulate the racing elements nor the rollable members after the racing elements are initially set into position and thereafter the game proceeds by the turning of a rotary conveyor for presenting the rollable members in position for striking engagement with the racing elements.

Still another object of the invention is to provide a racing game device which is not dependent upon the skill of the players so that children and adults may compete with equal interest and opportunity of winning.

With the foregoing and other objects in view, reference is now made to the following specification and accompanying drawings in which the preferred embodiment of the invention is illustrated.

In the drawings:

Fig. 1 is a top plan view of a game device constructed in accordance with the invention and illustrating the same with part of the housing in section for illustrating the underlying construction.

Fig. 2 is a longitudinal vertical sectional view taken approximately on line 2—2 of Fig. 1.

Fig. 3 is a longitudinal horizontal sectional view taken approximately on line 3—3 of Fig. 2.

Fig. 4 is a transverse vertical sectional view taken approximately on line 4—4 of Fig. 3.

Fig. 5 is a transverse vertical sectional view taken approximately on line 5—5 of Fig. 1.

Fig. 6 is a fragmentary perspective view of a portion of the inclined guide track and support therefor and illustrating the same with one of the racing elements arranged in the track.

2

Fig. 7 is a fragmentary vertical sectional view taken approximately on line 7—7 of Fig. 4.

Fig. 8 is a fragmentary transverse vertical sectional view taken approximately on line 8—8 of Fig. 7.

The invention is shown in the drawings in its application to a horse racing game in which a plurality of representations of horses with jockeys mounted thereon constitute the racing elements 10. It is to be understood however, that the same may consist of the representation of any desired animals or figures.

The game device includes a housing 11 consisting of a bottom wall 12, longitudinally extending side walls 13 and 14, front and rear end walls 15 and 16, and a top wall 17. The top wall 17 extends from the forward end wall 15 in inclined relation toward the rear and terminates in spaced relation from the rear end wall 16. Arranged upon the upper surface of the top wall 17 are a plurality of transversely spaced guide tracks 18 for the racing elements 10 which guide tracks are of channel shaped formation in cross-sectional configuration and extend the full length of the top wall 17 and at the rear thereof extend upwardly therefrom in sharply inclined relation. At their lower ends the guide tracks 18 protrude beyond the end wall 15 to thereby provide abutments against which pivotally mounted goal members 19 may be disposed in upstanding relation and in position to be struck by the racing elements for overturning the said goal members so as to indicate the end of the race and the winning racing element.

The racing elements are moved in the guide tracks 18 by means of rollable elements 20 such as steel balls which are deposited in the guide tracks at the upper ends thereof. The steel balls gain momentum as they travel down the inclined guide tracks and upon striking the racing elements propel the same forward, after which the balls roll into the guideways 21 formed by the transverse spacing of the guide tracks. Located beneath the top wall 17 is a rearwardly sloping wall 22 upon the upper surface of which are arranged a plurality of guide chutes 23 into which the balls 20 are deposited when the same drop through the openings 24 at the lower ends of the guide ways. The guide chutes 23 extend rearwardly substantially the full length of the housing in angular relation with reference to the side walls of the housing so as to dispose the lower ends at one side of cylindrical conveyors 25 respectively. The guide chutes 23 have side openings 26 at the lower ends thereof for delivering the balls to the cylindrical conveyors.

The cylindrical conveyors are designed for receiving the balls 20 from the guide chutes 23 and for elevating and discharging certain of the balls into the guide tracks 18 while some of the balls are delivered to return tracks 27 which balls roll down the same and are returned to the guide chutes 23. The return tracks 27 correspond in number with the guide chutes 23 and are supported by brackets 28 affixed to the bottom wall 12 to dispose the tracks alongside the conveyors respectively and in forwardly sloping relation above the guide chutes 23. The cylindrical conveyors 25 also correspond in number to the number of guide chutes 23 and as viewed from the forward end of the device the conveyors are respectively located to the left of the guide tracks 18 and guide chutes 23. The conveyors are affixed to a shaft 29 which is journaled for rotation in the side walls 13 and 14 of the housing 11 and is provided with a crank handle 30 for turning the same in a clockwise rotation as viewed from the left hand side of the device as shown in Fig. 2 of the drawings. The conveyors are provided with any desired number of pockets for receiving the balls 20 from the guide chutes 23. As illustrated in the drawings, each conveyor is provided with six pockets, certain of which such as the pockets 31 are constructed for receiving the balls from the guide chutes 23 and for elevating and discharging the same into the guide tracks 18 while the pockets 32 are constructed for receiving the balls from the guide chutes and for discharging the same into the return tracks 27.

The pockets 31 are of cubical formation each having opposite walls 33 and 34 which constitute the bottom and top walls thereof respectively when the pocket is located at the bottom of the conveyor and which walls slope from the open side 35 toward the rear wall 36 and the outer periphery of the conveyor. The said pockets also include opposite side walls 37 and 38 which are arranged in parallel planes and are canted rearwardly from the open side 35 to the rear wall 36. The arrangement of the said walls is such that the bottom wall 33 slopes away from the adjacent chute 23 when the pocket has been moved downwardly to its lowest position, as illustrated in Fig. 8 of the drawings, so that the balls will roll from the chute 23 through the side opening 26 and thence through the opening 35 in the pocket and will rest upon the end wall 33 and against the angularly disposed rearwardly directed side wall 37. When the pocket is elevated towards a position slightly in advance of its highest position above the shaft 29 the ball therein will roll from its said position to the opposite end wall 34 and opposite side wall 38 which walls are angularly directed toward the opening 35 so that the ball will be discharged therethrough and into the adjacent guide track 18. Constructed in this manner, the balls entering the pockets 31 will be elevated and before reaching its highest position above the shaft 29 will roll into their corresponding guide tracks 18 for striking engagement with the racing elements.

The pockets 32 are also of cubical formation each having a bottom wall 40 which slopes away from the open side 41 and towards the rear wall 36 of the conveyor when the pocket is at its lowest position adjacent the side opening 26 of the guide chutes 23. The pockets 32 also include a side wall 42 which is canted in angular relation from the open side 41 forwardly towards the rear wall 36 of the conveyor. The arrangement of these walls of the pockets 32 is such that the balls will

roll from the guide chute 23 through the side opening 26 and thence through the open side 41 of the pockets and will rest upon the bottom wall 40. When the pocket has been elevated to a position approximately 90° from its lowest position the ball will roll onto the side wall 42 which being inclined towards the open side 41 of the pocket will cause the ball to roll from the pocket onto the return chute 27 which will then roll down the chute 27 and again be deposited in the guide chute 23.

The racing elements 10 each include an elongated base 44 which is of a width to slidably engage in the guide tracks 18. The upper surface 45 of the base 44 is inclined from the rear to approximately midway of the length thereof for directing the balls from the guide tracks 18 onto the base for striking engagement against the pedestal portion 46 on which the representation of the racing figure is mounted. After striking the pedestal portion 46 the balls roll laterally down the inclined surface 47 at the rear of the pedestal portion 46. The rear face 48 of the pedestal portion 46 is angularly related with reference to the guide track 18 for directing the balls down the inclined surface 47 and onto the guideway 21 after striking the pedestal portion 46.

In playing the game the racing elements 10 are arranged in the guide tracks 18 at the starting position adjacent the rear of the top wall 17, the participants each selecting one of the racing elements. The balls 20 are initially deposited in the guide chutes 23 by dropping an equal number thereof through each of the openings 24. Any number of balls may be employed which would preferably be 32 or 40 when the game embodies 8 guide tracks as illustrated. The crank handle 30 is turned to rotate the cylindrical conveyors 25 so as to elevate the balls and deposit them into the guide tracks 18 at the upper ends thereof so that the same will roll down the guide tracks and upon striking the racing elements 10 will propel the same a short distance down the inclined tracks. The balls then roll into the guideways 21 and then through the openings 24 into the guide chutes and are again elevated by the conveyors 25 and the operation is continued until one of the racing elements has engaged and overturned the goal member 19 to win the race and end the game. It will be understood that during elevation of the balls by the conveyor member 25 certain of the balls enter the pockets 32 and are returned to the guide chutes 23 so that the number of balls that are deposited in the guide tracks 18 during the course of the game is uncertain. The cylindrical conveyors 25 are located on the shaft 29 with the pockets thereof disposed in staggered relation so that the several conveyors do not deposit the balls into the guide tracks 18 at the same time. The pockets 32 are equal in number in the several conveyors but the same are arranged in varying relation therein so that during a game the same number of balls may not be delivered to each guide track 18 nor may the same number of balls be returned to each of the guide chutes 23 whereby the racing element which first reaches the lower end of the guide tracks 18 is uncertain.

In order to increase the uncertainty of the delivery of the balls to the conveyors 25 the guide chutes 23 may be provided with obstructions such as upwardly projecting pegs 50 arranged in staggered spaced relation and projecting upwardly in said guide chutes so that

as the balls travel down the chutes the same engage against the said pegs to prevent the unobstructed rolling of the balls down the chutes.

What is claimed is:

1. In a game device, a plurality of inclined guide tracks adapted to receive racing elements and rollable members for propelling said racing elements by striking engagement of the rollable members therewith, inclined guide chutes located below said guide tracks and adapted to receive the rollable members after striking the racing elements, inclined return chutes located below said guide tracks and sloping toward said guide chutes for returning the rollable members received therein to said guide chutes respectively, rotatable conveyors arranged alongside of said guide tracks respectively and having side opening pockets for receiving the rollable members from the guide chutes and for elevating and directing the rollable members into said return chutes and guide tracks, certain of the pockets of each conveyor each having a front wall canted from the side opening in a direction opposite to the direction of rotation of the conveyor and an upper wall sloping from the side opening toward the periphery of the conveyor when the pocket is in its lowest position whereby the rollable members received in the pockets from the guide chutes will roll from said pockets onto said guide tracks at the rear of the racing elements when the pockets are rotated to a position above said guide tracks, and certain of the pockets of each conveyor each having a rear wall canted from the side opening in a direction corresponding to the direction of rotation of the conveyor when the pocket is in its lowest position whereby rollable members received in said last named pockets from the guide chutes will roll from said pockets onto said return chutes when the pockets are rotated to a position above said return chutes.

2. In a game device, a plurality of inclined guide tracks adapted to receive racing elements and rollable members for propelling said racing elements by striking engagement of the rollable members therewith, inclined guide chutes located below said guide tracks and adapted to receive the rollable members after striking the racing elements, inclined return chutes located below said guide tracks and sloping toward said guide chutes for returning the rollable members received therein to said guide chutes respectively, rotatable conveyors arranged alongside of said guide tracks respectively and having side opening pockets for receiving the rollable members from the guide chutes and for elevating and directing the rollable members into said return chutes and guide tracks, certain of the pockets of each conveyor each having a front wall canted from the side opening in a direction opposite to the direction of rotation of the conveyor and an upper wall sloping from the side opening toward the periphery of the conveyor when the pocket is in its lowest position whereby the rollable members received in the pockets from the guide chutes will roll from said pockets onto said guide tracks at the rear of the racing elements when the pockets are rotated to a position above said guide tracks, and certain of the pockets of each conveyor each having a rear wall canted from the side opening in a direction corresponding to the direction of rotation of the conveyor when the pocket is in its lowest position whereby rollable members received in said last named pockets from the guide chutes will roll from said pockets onto said return chutes when the pockets

are rotated to a position above said return chutes, and said conveyors being arranged with the pockets in each conveyor disposed in varying relation with the pockets in the other conveyors whereby the number of rollable members received by the guide tracks at the rear of the racing elements when the conveyors are rotated is uncertain and independent of the skill of the player.

3. In a game device, a plurality of inclined guide tracks adapted to receive racing elements and rollable members for propelling said racing elements by striking engagement of the rollable members therewith, inclined guide chutes located below said guide tracks and adapted to receive the rollable members after striking the racing elements, inclined return chutes located below said guide tracks and sloping toward said guide chutes for returning the rollable members received therein to said guide chutes respectively, rotatable conveyors arranged alongside of said guide tracks respectively and having side opening pockets for receiving the rollable members from the guide chutes and for elevating and directing the rollable members into said return chutes and guide tracks, certain of the pockets of each conveyor each having front and rear walls canted from the side opening in a direction opposite to the direction of rotation of the conveyor and upper and lower walls sloping from the side opening toward the periphery of the conveyor when the pocket is in its lowest position whereby the rollable members will roll into said pockets from the guide chutes and will roll from said pockets onto said guide tracks at the rear of the racing elements when the pockets are rotated to a position above said guide tracks, and certain of said pockets each having a rear wall canted from the side opening in a direction corresponding to the direction of rotation of the conveyor and each having a lower wall sloping from the side opening toward the periphery of the conveyor when the pocket is in its lowest position whereby the rollable members will roll into said pockets from the guide chutes and will roll from said pockets onto said return chutes when the pockets are rotated to a position above said return chutes.

4. In a game device, a plurality of inclined guide tracks adapted to receive racing elements and rollable members for propelling said racing elements by striking engagement of the rollable members therewith, inclined guide chutes located below said guide tracks and adapted to receive the rollable members after striking the racing elements, inclined return chutes located below said guide tracks and sloping toward said guide chutes for returning the rollable members received therein to said guide chutes respectively, rotatable conveyors arranged alongside of said guide tracks respectively and having side opening pockets for receiving the rollable members from the guide chutes and for elevating and directing the rollable members into said return chutes and guide tracks, certain of the pockets of each conveyor each having front and rear walls canted from the side opening in a direction opposite to the direction of rotation of the conveyor and upper and lower walls sloping from the side opening toward the periphery of the conveyor when the pocket is in its lowest position whereby the rollable members will roll into said pockets from the guide chutes and will roll from said pockets onto said guide tracks at the rear of the racing elements when the pockets are rotated to a position above said guide tracks.

tion above said guide tracks, and certain of said pockets each having a rear wall canted from the side opening in a direction corresponding to the direction of rotation of the conveyor and each having a lower wall sloping from the side opening toward the periphery of the conveyor when the pocket is in its lowest position whereby the rollable members will roll into said pockets from the guide chutes and will roll from said pockets onto said return chutes when the pockets are rotated to a position above said return chutes, and said conveyors being arranged with the pockets in each conveyor disposed in varying relation with the pockets in the other conveyors whereby the number of rollable members received 15 by the guide tracks at the rear of the racing

elements when the conveyors are rotated is uncertain and independent of the skill of the player.
